UNITED STATES PATENT OFFICE.

CHARLES L. RAYFIELD, OF CHICAGO, ILLINOIS.

MULTIPLE-JET CARBURETER.

1,224,207.

Specification of Letters Patent.

Patented May 1, 1917.

Application filed September 1, 1911. Serial No. 647,190.

To all whom it may concern:

Be it known that I, CHARLES L. RAYFIELD, a citizen of the United States, and a resident of the city of Chicago, in the county of Cook 5 and State of Illinois, have invented certain new and useful Improvements in Multiple-Jet Carbureters; and I do hereby declare that the following is a full, clear, and exact description of the same, reference being had 10 to the accompanying drawings, and to the numbers of reference marked thereon, which form a part of this specification.

This invention relates to improvements in carbureters of that class set forth in my prior 15 application for patent for "Carbureters", filed on the 8th day of December, 1909, Serial No. 532,114, (Patent No. 1,193,820 of Aug. 8, 1916.)

The object of the invention is to afford a 20 multiple jet carbureter in which at least one of the jets is automatically controlled to vary the supply of fuel with the adjustment of the throttle.

It is also an object of the invention to 25 afford a construction of the class described in which an air inlet port or ports are provided for each jet, positioned to conduct the air across the jet when in operation.

It is a further object of the invention to 30 afford a construction in which a residual supply of gasoline or other hydro-carbon fuel is maintained at all times in the path of the inflowing air, to assist in initial carburation, and to afford a large vaporizing 35 area exposed to the inflowing air.

It is also an object of the invention to afford a construction adapted for ready adjustment to insure satisfactory control of the richness of the mixture under all conditions.

40 The invention consists in the matters hereinafter described, and more fully pointed out and defined in the appended claims.

In the drawings:

45 Figure 1 is a side elevation of a device embodying my invention.

Fig. 2 is a view in elevation of the opposite side of the carbureter.

Fig. 3 is a longitudinal vertical section with parts shown in elevation.

50 Fig. 4 is a section on line 4-4 of Fig. 3.

Fig. 5 is a section on line 5-5 of Fig. 3.

Fig. 6 is a fragmentary section on line 6-6 of Fig. 1, with parts omitted.

Fig. 7 is a central section taken through 55 the adjusting cam for one of the jets.

Fig. 8 is a section on line 8-8 of Fig. 2.

Fig. 9 is a fragmentary top plan view of the carbureter with parts omitted.

As shown in the drawings:

Said carbureter comprises connected casings 1 and 2, affording a float feed chamber A, and a mixing chamber B. Said chambers, as shown, are cylindric. The casing 1, for the float feed chamber comprises cylindric side walls, and an integral bottom wall 3, having a central or axial downwardly directed tubular boss 4, integral with the bottom thereof, and opening upwardly thereinto, and closed at its lower end by means of a screw plug 5, threaded thereinto, and engaging a suitable packing washer 6, between the same and the end of said boss to seal the same.

The cover 7, for the float feed chamber, is removably secured thereto, and extending axially through said chamber, and a suitable central aperture in said cover, is a rod 8, of a length to extend into the bore in said boss 4, as shown in Fig. 3, and to normally extend slightly above the cover. Adjustably 80 (but rigidly) secured on said rod, is a float 9, in the present instance shown as constructed of sheet metal, and having a sleeve 10, extending centrally therethrough, and through which the rod 8, extends. Said float feed chamber, is cored from the side adjacent the mixing chamber, to afford an inward extension C, of the chamber in the space between the same and said mixing chamber, and as shown, the casing of the mixing chamber B, is constructed to afford a rearward extension D, of the chamber, extending over said extension of the float feed chamber C, and to the wall of the float feed chamber, said chamber D constituting a carbureting chamber.

The bottom of said extension C, of the float feed chamber, is provided with an aperture therethrough, and threaded therein at its upper end, is a cylindric plug 11, which serves to close the bottom of that portion of the float feed chamber and is provided with a central upwardly opening recess or bore therein, communicating with a restricted central bore extending therethrough, 100 which affords the seat for the inlet needle valve, through which the flow of the hydro-carbon fuel into the float feed chamber is controlled. Said plug is provided on its lower end, with a peripheral downwardly extending internally threaded flange 12, and threaded thereinto is a hollow connection 13,

having a screen 14, stretched across the top thereof. The induction pipe 15, whereby the gasoline tank communicates with the float feed chamber is threaded into said connection 13.

The horizontal partition 16, between the extension D, from the mixing chamber, and the extension C, from the float feed chamber forming the bottom of one and the top of the other is provided with an aperture there-through, and threaded therein in alinement with the corresponding seat in the plug 11, is the tubular nozzle or jet pipe 17, the upper end of which extends above the floor 16, in said extension of the mixing chamber and the lower end of which extends below said partition 16. Slidably and loosely engaged thereon in the extension C, of the float feed chamber, is a sleeve 18, which, near its lower end, is restricted and tapered to a point to afford the valve closure 19, to seat within and to close the induction passage through the plug 11. Said sleeve 18, is provided with apertures 18* therein slightly above the bottom of the float feed chamber, to admit the fluid from said float chamber thereinto, and a peripheral flange 20, is provided on said sleeve intermediate its ends, as shown in Fig. 3. A weak spring 21, is engaged around said sleeve and bears at its upper end on the wall 16, and at its lower end on said flange to hold the lower needle valve normally closed when the float feed chamber is sufficiently full to support the float.

35 Removably secured in the float feed chamber on the bottom thereof, is a projection 22, and pivotally engaged thereon is a lever 23, the shorter end of which is yoked to engage around the sleeve below the flange 20, and the longer end of which is provided with an aperture therethrough to receive the rod 8. As shown, a diametrically apertured ball 24, is rigidly secured on said rod 8, and seats on said longer end of the lever 23, to afford a self-adjusting bearing for the float on said lever.

Said plug 11, is provided with a passage 25, extending downwardly from its inner end to a passage 26, extending peripherally around the same, and a shallow cup 27, preferably metallic, and secured on the bottom of the mixing chamber by means of bolts, and spaced a distance therefrom, as shown in Figs. 1 to 3 inclusive, is provided with an integral arm or extension 28, having a bore therethrough, in which said plug 11, fits closely.

As shown, packing washers 29, are provided above and below said arm, and through which said plug extends to seal the joint therebetween. A passage 30, extends through said arm and communicates with the peripheral passage 26, of said plug. Communicating with said passage and extending through said cup or saucer to near

the middle of the mixing chamber, is a tubular jet nozzle 31. As shown, a cap screw 32, is set in the under side of said saucer or cup co-axially with said nozzle or jet, to afford access thereto for the purpose of cleaning or in assembling.

Integral with the rear wall of the mixing chamber, or, in other words, directed toward the float feed chamber, is a bracket or arm 33, having a cylindric seat in the under side thereof co-axial with the bore of the jet nozzle 17, and engaged therein at its upper end, and extending through the top wall 34, of the carbureting chamber D, is a needle valve closure 35, for said jet nozzle 17. A spring 36, engaged in said seat in the arm 33, bears on the upper end of said needle valve closure to hold the same normally seated.

Journaled in a suitable bearing on the rear wall of the mixing chamber, is a transverse shaft 37, and secured thereon and projecting into a slot in the stem of the needle valve closure 35, is a finger 38, which acts with the rotation of said shaft 37, to raise said needle valve closure against the tension of the spring 36.

At the upper end of the casing affording the mixing chamber, is provided an outwardly extending flange 39, which may be apertured to afford engagement with the manifold pipes leading to the engine. Extending through said mixing chamber are parallel shafts 40 and 41, above and below the carbureting chamber D respectively, and rigidly but adjustably secured thereon are butterfly valve closures 42 and 43, respectively. The upper butterfly valve closure 42, is slightly cut away on one side thereof to afford a sufficient passage for the mixture to the manifold pipes to support combustion when the throttle is substantially closed or at its lowest running adjustment.

The lower butterfly valve closure 43, is slotted on its front edge to receive the jet nozzle 31, therein, as shown in Fig. 3, when the valve is closed, and is also slotted at its opposite side and provided with a downwardly extending boss or projection 44, to which is pivotally engaged the lower end of a rigid link or connecting rod 45, the upper end of which is pivotally engaged on a corresponding projection 46, on the upper butterfly valve closure, so that adjustment of one of said valves by the rotation of the shaft thereof, necessitates an adjustment of the other through the medium of said link.

Secured on the outer end of the shaft 40, is the throttle lever 47, whereby said shaft may be rotated, and said butterfly valves adjusted. Also rigidly secured thereon is a rectangular block 48, at the inner side of the throttle lever, and slidably and adjustably secured thereon is a cam 49, comprising cam faces arranged approximately at right angles to the axis of the lever 47.

angles to each other, and the angle formed thereby cut away to afford a rounded continuation of the cam, as shown in Fig. 7. A screw shaft 50, journaled in the ends of said cam block, is threaded through said block 48, and extending through a notch in the shaft 40, is provided on its outer end with an adjusting wheel 51, whereby the cam may be shifted on said block with reference to its center of rotation, to-wit, its shaft 40. One end of said screw shaft 50, is milled, and yieldingly engaged in the adjustable cam block, is a spring pressed detent 52, adapted to engage the milled surface of the shaft to hold the same in adjusted position.

Loosely engaged on the shaft 37, for adjusting the needle valve closure 35, is a downwardly and forwardly extending arm 53, provided at its forward end with a bearing plate 54, removably secured thereon and engaging said movable cam member 49, and adapted by engagement therewith to actuate said lever and the shaft 37, to operate said needle valve. Integral with the arm 53, is a downwardly extending arm 55, provided with a set screw 56, extending therethrough and rearwardly beyond the same.

Rigidly secured on said shaft 37, by means of a bracket arm 57, is a sleeve 58. Journaled in said sleeve is a shaft 59, having rigidly secured on the lower end thereof a cam or eccentric 60, which bears against the rearwardly extended end of the set screw 56, to actuate the shaft 37, when the shaft 59, is rotated. Slight movement of the arm 55, on the shaft 37, is afforded, so that rotation of the cam 60, against the adjusting screw, serves to swing the lower end of the sleeve 58, rearwardly, thereby elevating the finger 38, secured on said shaft, and slightly opening the needle valve admitting to the carbureting chamber D. A lever 61, is rigidly secured on the upper end of the shaft 59, to rotate the same, and a rod 62, is pivotally secured to the extremity of said lever by means of a set screw 63, and extends rearwardly through a suitable bracket 64, to permit of manual engagement to open said needle valve preparatory to starting the carburation.

Rigidly secured on the shaft 40, at the opposite side of the carbureter, is an arm 65, provided with a set screw 66, adapted to engage on a projection or lug 67, on the outer wall of the closure, as shown in Fig. 1. As shown, a set screw 68, is employed for engaging said arm 65, on the shaft. Said set screws 66 and 68, afford means for adjusting said arm to limit the degree of closure of the butterfly valves to the required amount to maintain a sufficient supply of the mixture to the motor to maintain the combustion at the lowest speed of

A supply of air is provided for each of the inlet jets. As shown, an air inlet port is provided opening into the extension D, of the mixing chamber slightly at the rear thereof, and a peripheral flange or tubular extension 69, in the wall of the casing, is provided around said port, and extends outwardly substantially flush with the side walls of the casing, as shown in Fig. 4, and, as shown, the passage therethrough tapers inwardly to conduct the air in a strong inflowing current or jet against the jet of the hydro-carbon as it comes from the needle valve, thus spraying and thoroughly vaporizing the same and carrying the same therewith into the mixing chamber B, between the butterfly valves 42 and 43. As shown also, a slight elevation or rib 70, is provided on the floor of the carbureting chamber D at the point where the same communicates in the main mixing chamber, thereby serving to maintain a thin film of the hydro-carbon fuel on the floor of said mixing chamber extension to expose a large surface to vaporization.

An air inlet port is also provided to deliver inflowing air to and across the top of the jet nozzle 31. For this purpose, as shown, a suitable aperture is provided in the wall of the mixing chamber and threaded thereinto is a spider 71, at the hub of which is secured a shaft or stud 72, which extends outwardly therefrom and secured on which, and bearing against the hub of the spider, is a relatively strong spiral spring 73, coiled oppositely about which and on the outer side thereof, is a longer and weaker spiral spring 74. Slidably engaged on said stud 72, is a valve disk 75, provided on its inner side with a hub 76, adapted to engage the stronger 105 inner spring 73, when moved inwardly sufficiently into an open position and normally held from engagement therewith and against its seat by the weaker spring 74, which engages against said disk.

Threaded upon the outwardly extending annular rim 77, of said spider, is a casing 78, having an outwardly flaring nozzle 79, thereon, as shown in Fig. 3, and affording an inner seat against which said disk 75, engages, 115 as shown in Fig. 3, when the air valve is closed.

As shown, the periphery of said casing is longitudinally grooved on the outer side, and a spring pressed detent 80, is engaged in a suitable bracket or arm 81, secured upon the wall of the mixing chamber, and engages in said longitudinal grooves or recesses to hold said casing in adjusted position. Of course, when the casing is adjusted inwardly, the tension of the springs against the closure 75, is increased thereby, while outward adjustment decreases such pressure, thereby affording a larger supply of air for the mixture.

As shown, a tubular casing or hood 82, closed at its upper end, is threaded upon a central boss 83, on the cover of the float feed chamber to exclude dust and dirt, therefrom. Said boss, as shown, is also provided with a vent passage therethrough from the float feed chamber to vent said chamber against internal pressure. Pivotally engaged in said hood, and extending 10 through a slot in the side wall thereof, is a bent lever, one arm 84, of which extends over and into position to engage the rod 8, when the float feed chamber is filled to normal capacity. The other end 85, of said lever, extends downwardly on the outer side of said hood, and is engaged by a suitable rod to permit manual actuation, thereby holding the rod 8, with the float thereon, downwardly, until the carburetor is slightly 20 flooded to facilitate starting the carburation. A spring 86, is engaged on said lever and acts to hold the arm 84, upwardly out of position with said rod 8, as shown in Fig. 3.

25 In the drawings, the mixing chamber of the carburetor is shown cored to afford an exterior water jacket E, and suitable pipe connections 87 and 88; are afforded thereover to connect the same to the radiator 30 water, if desired. However, such a water jacket may or may not be provided, depending in part on the size of the carburetor, the capacity required, and the character of the use for which intended.

35 The operation is as follows:

The carburetor having been assembled and suitably connected with the manifold pipes or the engine, and with the fluid supply pipe from the tank, is adjusted to regulate 40 the air supply through the automatic valve 75, and to regulate the inlet through the needle valve nozzle 17, in the carbureting chamber D. The adjustment for the needle valve 35, is effected by shifting the 45 cam 49, relatively the shaft 40, by means of the screw shaft 50, to vary the degree of opening to the throttle requirements so that the needle valve will be sufficiently opened to maintain the combustion at the lowest engine rate when the butterfly valves in the 50 mixing chambers, are approximately closed. A wide range of adjustment is afforded by means of said cam, and practically any inlet requirements can be secured thereby, and 55 when adjusted for the lowest engine rate, a further degree of opening of the valve may be secured by means of the cam 60, which serves to rotate the shaft 37, slightly in the arm 55, against which said cam acts, there- 60 by permitting the needle valve to be further opened in slightly flooding the carburetor to begin the carburation.

This also is facilitated, by means of the tickler lever on the float feed chamber, 65 whereby the float might be held depressed

and the inlet needle valve 19, held open to permit flooding of the float feed chamber. The automatic air valve, of course, is adjusted, so that normally, its closure is out of engagement with the relatively strong inner coiled spring 73, and is held in closed position by the lighter spring. Said heavier spring, however, serves to resist the inward movement of said closure as it approaches the full requirement for the air supply for the second inlet jet. By adjusting the casting for said automatic valve inwardly or outwardly, substantially any air inlet requirements may be attained.

The inlet jet in the mixing chamber, is 70 normally open at all times, and the extremity thereof being positioned between the butterfly valves, said jet is practically out of action when the engine is throttled low, owing to said butterfly valves being substantially closed, as well also as the automatic air inlet valve. The rear or inlet port, however, or that for the needle valve 35, in the carbureting chamber D remains in action, and a sufficient amount of carburation is 75 effected thereby to maintain a low engine rate as required, the mixture escaping therefrom to the manifold pipes through the notch or clearance afforded in the rear edge of the upper butterfly valve closure, which is 80 just above the mouth of the carbureting chamber D when said butterfly valve is substantially closed.

As the throttle is opened wider, the second needle jet is brought more fully into 85 action, as well as the automatic valve, owing to the more rapid exhaustion of the mixture from the mixing chamber. In consequence, the automatic valve admits its quota of air which flows past, over and around the end of said nozzle, thoroughly vaporizing and mixing with the jet therefrom, and also mixing with the mixture from the carbureting chamber D. Any excess of gasoline or 90 hydro-carbon fuel from the jet 31, flows down into the cup 27, below the lower open end of the mixing chamber, and the air drawn inwardly over the same, rapidly vaporizes the same, and carries it inwardly to 95 mingle in the mixing chamber with that from the two jets aforesaid, so that a large quantity of mixture is thereby afforded immediately and to supply the highest engine rate of combustion.

Of course, inasmuch as the inlet to the 100 float feed chamber and the outlet therefrom to the carbureting chamber D, are controlled each by a needle valve, the arrangement whereby said needle valves are co-axially arranged and supported in place, affords the 105 utmost convenience for assembling, adjustment, inspection or repair and exceedingly simplifies the construction in all respects.

It is to be understood, of course, that 110 details of the construction may be varied

through a wide degree. I have shown a preferred form of my invention, although numerous modifications and variations are, of course, possible. I therefore do not purpose 5 limiting the patent granted, otherwise than necessitated by the prior art.

I claim as my invention:

1. A carbureter comprising a casing affording a mixing chamber, jet nozzles 10 adapted to direct the hydro-carbon fluid thereinto, a throttle valve, means for regulating the inlet from one of the nozzles simultaneously and correspondingly with adjustment of the throttle valve, ports for 15 admitting air into the mixing chamber across the discharge for the nozzles, an automatically operated normally closed air valve and a second air valve connected to the throttle valve so as to open said second 20 air valve when the throttle is adjusted in excess of normal running position.
2. A carbureter comprising a casing affording a source of hydro-carbon supply and a mixing chamber, nozzles connected 25 with said source of supply and adapted to direct the hydro-carbon fluid into the mixing chamber, a throttle valve, an adjustable cam for regulating the inlet from one of the nozzles simultaneously with the adjustment 30 of the throttle valve, a plurality of ports for admitting air into the mixing chamber, two of the same directing the inlet air across the discharge for the hydro-carbon nozzle, a mechanically operated normally closed 35 air valve, and connections between said air valve and the throttle valve for opening said air valve when the throttle valve is adjusted in excess of normal running position.
3. In a carbureter a float chamber, a mixing chamber, a throttle valve controlling the flow therefrom, a nozzle in open communication with said float chamber for spraying the hydro-carbon thereinto, and projecting 40 into said mixing chamber, a nozzle and needle valve therefor, a passage connecting said last mentioned needle valve to said float chamber, air inlet ports including an automatic valved port, a butterfly valved port, 45 and an open port, and connections between said butterfly valve of one port and said throttle valve for opening the former with opening movement of the latter.
4. In a carbureter of the class described a mixing chamber, means for discharging hydro-carbon fluid thereinto at a plurality of different points at different levels and removed from one another, a float valve controlling the flow of the fluid into the carbureter, a normally open air inlet communicating laterally at one side of said mixing chamber and adjacent one of said hydro-carbon inlet means, another automatically 50 valved inlet communicating laterally in said mixing chamber opposite to said first men-
- tioned inlet, and adjacent another of said hydro-carbon fluid inlet means, a throttle valve in said mixing chamber controlling the flow therefrom, and a butterfly air inlet valve in said mixing chamber connected 70 to said throttle valve and controlling the flow of air into said mixing chamber.
5. In a carbureter the combination with the throttle valve, of a pair of normally closed auxiliary air valves, a cam actuated 75 hydro-carbon needle valve, connections between one of said air valves and the throttle valve and the needle valve to cause said valves to open proportionately with the opening of the throttle, and a second hydro-carbon inlet operating independently of said valves.
6. In a carbureter, a mixing chamber, a cam actuated hydro-carbon inlet valve, an auxiliary normally closed air valve opening 80 into said mixing chamber, a spring actuated automatic air valve, a hydro-carbon inlet adjacent thereto, a throttle valve, and connections between said auxiliary air valve, the throttle valve, and the hydro-carbon 85 valve, to actuate the same to open said valves proportionately with the opening of the throttle.
7. In a carbureter of the class described, a fuel inlet, a mixing chamber, a normally 90 open air inlet passage communicating laterally therein, another air inlet communicating through the opposite side of said mixing chamber, and an air inlet in the bottom 95 of said mixing chamber, said second mentioned air inlet provided with an automatically acting valve and a manually operable valve controlling the flow through said third mentioned air inlet to the mixing chamber.
8. In a carbureter the combination with a casing affording a mixing chamber, a plurality of hydrocarbon inlets adapted to admit fuel thereinto, a throttle valve controlling the flow of fuel mixture therefrom, of a plurality of air inlet ports, two thereof disposed opposite to one another and communicating laterally in said mixing chamber, the one normally open and the other automatically controlled, and a third inlet port the opening and closing of which is governed directly by movement of the throttle valve.
9. In a carbureter, the combination of a 100 casing affording a mixing chamber, an auxiliary mixing chamber communicating laterally therewith, an automatically controlled air inlet also communicating into said mixing chamber and disposed opposite to said auxiliary mixing chamber, hydro-carbon inlets in each of said chambers, and air inlet ports adjacent each of said hydro-carbon inlets.
10. In a carbureter the combination with a casing affording a float and mixing cham-

- ber, said mixing chamber having a normally open air inlet port, of a hydro-carbon nozzle and needle valve therefor disposed in the path of air entering through said port, a 5 throttle valve in said mixing chamber controlling the flow from the carburetor, a fuel nozzle communicating with said float chamber and projecting into the mixing chamber at a point beneath said throttle valve, an 10 air inlet valve controlling the admission of air into said mixing chamber and disposed below said fuel nozzle and connected with said throttle valve for simultaneous actuation therewith, and an automatic air valve 15 controlling another passage leading into said mixing chamber for the admission of air over said fuel nozzle under wide open conditions of the throttle valve.
11. In a device of the class described a 20 plurality of mixing chambers, hydro-carbon inlets in each thereof, butterfly valves in one of said mixing chambers, connections between said butterfly valves and the hydro-carbon inlet of the other mixing chamber, 25 and a normally open air port adjacent said hydro-carbon valve.
12. In a device of the class described a 30 plurality of mixing chambers communicating with one another, hydro-carbon inlets in each thereof one of which is normally open, means controlling the flow of mixture from one of said mixing chambers simultaneously with the flow of hydro-carbon to the inlet in the other of said chambers, a normally 35 open air port adjacent said normally open hydro-carbon inlet, and a plurality of air ports adapted to admit air across the other of said hydro-carbon inlets.
13. In a multi-jet carburetor a mixing 40 chamber, a throttle valve controlling the outlet therefrom, an air valve at the bottom of the mixing chamber controlling the inlet of air directly to said mixing chamber and operatively connected with said throttle 45 valve, an automatic air valve connected laterally in said mixing chamber, an inlet fuel valve, the area of opening of which changes proportionately with the movement of said throttle and air valves, and a fuel inlet communicating directly in said mixing chamber 50 and of constant area of opening at all times.
14. In a multi-jet carburetor a mixing chamber, a plurality of fuel inlets therefor, a throttle valve in said mixing chamber 55 controlling the outlet therefrom, operative connections between said throttle valve and one of said fuel inlets to vary the area therethrough proportionately with the opening of said throttle valve, said other fuel inlet 60 of constant area at all times, and a plurality
- of air inlet ports, one normally open at all times, another the area of opening of which changes proportionately with movement of said throttle valve, and another the area of opening of which is dependent upon the 65 draft exerted by the engine.
15. In a device of the class described a 70 mixing chamber, an outlet valve controlling the flow therefrom, a plurality of fuel inlets for admitting fuel into said mixing chamber, one of said fuel inlets operatively connected with the valve therein whereby the area of opening through said fuel inlet is varied proportionately with movement of said valve, the other fuel inlet of constant 75 area at all adjustments of said mixing chamber outlet valve, mechanism for changing the adjustment of the operative connections between said mixing chamber outlet valve and variable area fuel inlet to change the 80 relative proportionate movements thereof, and air inlet ports disposed opposite one another and communicating laterally into the mixing chamber, the one normally open and the other adapted to open due to suction 85 within the mixing chamber.
16. In a carburetor, the combination with a casing formed into a float chamber, a mixing chamber, and a carbureting chamber, of a hydro-carbon needle valve opening into 90 said carbureting chamber, an air inlet port for said carbureting chamber, a throttle valve at the upper end of said mixing chamber, a feed nozzle projecting into the lower end of said mixing chamber and communicating with said float chamber, an automatic 95 horizontally-disposed air inlet valve positioned adjacent said fuel nozzle to admit air into the mixing chamber, and adjustable connections between the throttle valve and 100 needle inlet valve.
17. The combination with a carburetor and its needle and throttle valves, of an air valve opening into the mixing chamber at the lower end thereof, a cam on said throttle 105 valve adapted to actuate said needle valve, mechanical connections disposed within the mixing chamber for actuating said air valve in accordance with movements of the throttle valve, an automatic air inlet valve in the 110 side of the mixing chamber, and an auxiliary fuel nozzle within the mixing chamber adjacent said automatic air inlet valve.
- In testimony whereof I have hereunto 115 subscribed my name in the presence of two subscribing witnesses.

CHARLES L. RAYFIELD.
